CLAIM

The ornamental design for a mobile arched telescopic deployable stage system, as shown and described.

DESCRIPTION

FIG. 1 is a front view of a mobile arched telescopic deployable stage system of the invention.

FIG. 2 is a top, front perspective view thereof.

FIG. 3 is a rear view thereof.

FIG. 4 is a left side view thereof, the right side being a mirror image thereof.

FIG. 5 is a top view thereof.

FIG. 6 is a top, front right perspective view thereof.

FIG. 7 is a top, rear right perspective view thereof.

FIG. 8 is a top rear perspective view thereof; and,

FIG. 9 is a top right perspective view thereof, shown in an alternate configuration of use.

The vertical dashed lines in FIG. 4 illustrate the side edges of the outermost panels and form part of the claimed design.
